(57) **CLAIM**

The ornamental design for a corkscrew with integral intelligent thermometer, as shown and described.

DESCRIPTION

FIG. 1 is a front view of a preferred embodiment of the corkscrew with integral intelligent thermometer in the closed position.

FIG. 2 is a rear view of a preferred embodiment of the corkscrew with integral intelligent thermometer in the closed position.

FIG. 3 is a right side view of a preferred embodiment of the corkscrew with integral intelligent thermometer in the closed position.

FIG. 4 is a left side view of a preferred embodiment of the corkscrew with integral intelligent thermometer in the closed position.

FIG. 5 is a front side view of a preferred embodiment of the corkscrew with integral intelligent thermometer with the corkscrew, and the lever arm with integral thermometer, in the open position.

FIG. 6 is a right side view of a preferred embodiment of the corkscrew with integral intelligent thermometer with the corkscrew, and the lever arm with integral thermometer, in the open position. The lever arm with integral thermometer is shown touching a bottle to measure the temperature. The broken line showing of a bottle is for illustrative purposes only and forms no part of the claimed design.

FIG. 7 is a left side view of a preferred embodiment of the corkscrew with integral intelligent thermometer with the corkscrew, and the lever arm with integral thermometer, in the closed position, and the cutting blade in the open position.

FIG. 8 is a distal end view of a preferred embodiment of the corkscrew with integral intelligent thermometer.

FIG. 9 is a proximal end view of a preferred embodiment of the corkscrew with integral intelligent thermometer.

FIG. 10 is a front side view of a second embodiment of the corkscrew with integral intelligent thermometer. The other views are the same as the first embodiment except this embodiment does not have a recording option; and,

FIG. 11 is a front side view of a third embodiment of the corkscrew with integral intelligent thermometer. The other views are the same as the first embodiment except this embodiment does not have a recording option or a speaker option.
